Patented Feb. 20, 1973

226,348

CAN OPENER

Theodorus Cornelis Marie van der Kroft, Valkenswaard,
Netherlands, assignor to Van Eldersen's Metaalwaren-
fabriek "Brabantia," N.V., Aalst, Netherlands

Filed Feb. 22, 1971, Ser. No. 117,866

Term of patent 14 years

Int. Cl. D7—04

U.S. Cl. D8—39

FIG. 1

FIG. 2

FIG. 3

FIG. 4

FIG. 5

FIG. 6

FIG. 7

FIG. 1 is a front elevational view of a can opener in the closed position, showing my new design;

FIG. 2 is a top plan view thereof;

FIG. 3 is an end view from the right in FIG. 1;

FIG. 4 is a rear elevational view thereof;

FIG. 5 is a bottom plan view of the can opener as shown in FIG. 4;

FIG. 6 is an end view from the left in FIG. 1; and

FIG. 7 is a view similar to FIG. 4 but showing the can opener in an open position.

I claim:

The ornamental design for a can opener, as shown.
